CLAIM

The ornamental design for a fascia gun, as shown and described.

DESCRIPTION

FIG. 1 is a first perspective view of a fascia gun showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is an enlarged view of the selected portion in FIG. 1. The broken lines shown in the drawings depict portions of the fascia gun in which the design is embodied that form no part of the claimed design.
